Alfred E. Drissner, Cleveland, Ohio, assignor to
The National Acme Company, a corporation of
Ohio

Application November 4, 1948, Serial No. 149,470

Term of patent 14 years

(Cl. D54—6)

To all whom it may concern:

Be it known that I, Alfred E. Drissner, a citizen of the United States, in the city of Cleveland, county of Cuyahoga, and State of Ohio, have invented a new, original, and ornamental Design for a Single Spindle Automatic Chucking Machine, of which the following is a specification, reference being had to the accompanying drawing, forming a part hereof:

Figure 1 is a front elevational view of a single spindle automatic chucking machine showing my new design;

Figure 2 is a rear elevational view thereof;

Figure 3 is a side elevational view looking at the right hand side thereof as viewed in Figure 1;

Figure 4 is a side elevational view looking at the left hand side thereof as viewed in Figure 1.

I claim:

The ornamental design for a single spindle automatic chucking machine, substantially as shown.

ALFRED E. DRISSNER.
